UNITED STATES PATENT OFFICE.

CHARLES C. HUGHES, OF PHILADELPHIA, PENNSYLVANIA.

ARC-LAMP.

No. 903,861.

Specification of Letters Patent.

Patented Nov. 17, 1908.

Application filed October 13, 1906. Serial No. 338,766.

To all whom it may concern:

Be it known that I, CHARLES C. HUGHES, a citizen of the United States, residing at Philadelphia, in the county of Philadelphia,

5 State of Pennsylvania, have invented certain new and useful Improvements in Arc-Lamps; and I do hereby declare the following to be a full, clear, and exact description of the invention, such as will enable others 10 skilled in the art to which it appertains to make and use the same.

This invention relates to electric arc lamps of the hot wire type, that is wherein the feed is effected through the medium of a mechanism including as an element a thermo-expansive wire.

The object of the invention is to provide an alloy for use in the making of the wire, which alloy will have a high coefficient of 20 expansion, will have a sufficiently high tensile strength to suit the working conditions to which it is subjected, and the efficiency of which will not be impaired when subjected to high temperatures.

25 A still further and important object of the invention is to produce an alloy which will not only have a high coefficient of expansion but which will be quickly responsive to changes in temperature.

30 Numerous attempts have been made to produce a commercially practical lamp of this nature because of its cheapness of manufacture but the difficulty encountered is the proper material for the thermo-expansive 35 element.

In connection with the disclosure of the particular alloy employed, will be illustrated and described a type of alloy in which the wire has been and is being used.

40 In the drawings: Figure 1 is a view in elevation of the lamp, and, Fig. 2 is a similar view, but taken in a vertical plane at right angles to the plane of Fig 1.

The alloy of which the thermo-expansive 45 wire is formed, consists of copper fifty-seven and one-half per cent., nickel forty-two per cent. and lead one-half of one per cent. Of course it will be understood that these specific portions of the alloy may be varied as 50 may be found desirable and I do not wish to be limited to the exact proportions specified. Furthermore I may employ the equivalents of the elements mentioned should they be found to exist.

55 Referring now to the drawings in which there is illustrated a lamp of the hot wire

type, in which the present alloy is used, the numerals 5 and 6 denote upper and lower plates, respectively, which are held in fixed spaced relation by means of standards 7, 60 there being connected with the upper plate 5 the usual hanger 8 by means of which the lamp may be suspended, and with the lower plate 6, the usual globe supporting device 9.

Extending downwardly from the lower 65 plate 6 is the usual arm 10 which carries at its lower end the usual collar 11 for the reception of the lower end of the lower carbon of the lamp.

Secured to the under side of the upper 70 plate 5 is a plate 12 to which is secured the upper ends of depending guide-rods 13, the said rods being connected at their lower ends to brackets 14 which extend inwardly from the standards 7 and overlap at their meeting 75 ends. A collar 15 is arranged for the reception of the upper end of the upper carbon 16 of the lamp, the said carbon being held in place by means of a set-screw 17 which serves also as a binding post, as will be presently 80 explained.

Extending from diametrically opposite points upon the collar 15 are tongues 18 which are provided with apertures through which extend the rods 13, it being understood 85 that the said rods serve to guide the movement of the upper carbon and that the said carbon extends through an opening formed in the brackets 14 to further guide the same.

90 Mounted upon the upper face of the upper plate 5 is a binding post 19 which includes a downwardly extending arm 20 to which arm is connected one arm of an angle bracket 21, the other arm of the angle bracket being 95 apertured for the engagement of a threaded stem therethrough, the said stem being adjustable with respect to its relative arm by means of a milled nut. Connected with the threaded stem is one end of a conductor wire 100 22 formed from the alloy above described which extends downwardly as shown in Fig. 1 and around an insulated roller 23 journaled upon a plate 24 which is secured to the adjacent one of the standards 7 adjacent 105 its lower end. The wire 22 extends upwardly and over a similar roller 25 which is journaled in a bearing bracket 26 secured to the under side of the top plate 5 and over a third roller 27 journaled in a bearing bracket 28 110 which is also secured to the under side of the said plate. After passing over the roller

27, the wire extends downwardly and around an insulated roller 29 and thence upwardly and is connected to a binding post 29' which is connected to the top plate 5.

5 The roller 29 is journaled in a yoke bearing 30 which is pivotally connected to one end of an arm 31 which is pivotally mounted upon a plate 32 which is secured to the adjacent one of the standards 7, the said connection between the yoke-bearing and the pivoted arm being made adjustable by providing the arm with a series of openings 33 through which may be interchangeably engaged the pivot pin which connects the 15 members.

The plate 32 is provided with a bracket arm 34 to which is secured the lower end of a plate 35, the upper end of which is bent laterally at right angles and provided with an 20 aperture through which is loosely engaged a threaded stem 36 upon which is engaged an adjusting nut 37 which latter bears against the said portion of the plate 35. A helical spring 38 is connected at one of its 25 ends to the lower end of the stem 36 and is arranged for the engagement of its other end with one of a series of openings 39 formed through the said arm.

Slidably disposed upon the upper carbon 30 16 of the lamp is a sleeve 40 which is provided adjacent its lower end and upon opposite sides with pairs of spaced fingers between which are received the respective guide rods 13 to prevent turning of the 35 sleeve upon the carbon 16. The sleeve is also provided with a pair of spaced apertured ears between which is pivoted one end of an arm 41, the point of pivotal connection of the said arm with the sleeve being adjacent what may be termed the lower 40 longitudinal edge of the arm for a purpose to be hereinafter described. The arm 41 rests against the end of the pivoted arm 31, the said end of the arm 31 being preferably 45 reduced to form a stem 42 and the end of the arm 41 is preferably weighted as at 43 to normally hold it against the stem 42. The sleeve 40 is provided at a point in alignment with the upper end of the arm 41 with a slot 50 44 through which the said upper end of the arm may project to contact with the upper carbon 16, it being understood that the end of the arm contacts frictionally with the said carbon when the arm is raised by reason of the location of the pivot point of the 55 arm adjacent the lower longitudinal edge thereof, and it will also be understood that when the arm is lowered, its upper end will be moved out of engagement with the upper 60 carbon 16 thereby permitting downward movement of the said carbon.

Connected to the binding post 17 is one

end of a conductor wire 45 which wire is connected at its opposite end to the binding post 29'. The arm 10 has its upper end reduced and screw threaded and engaged through the lower plate 6 and engaged upon the said screw-threaded end of the arm is a nut 47 which, together therewith forms a binding post for the attachment of one end 65 of a conductor wire 48 which is connected at its opposite end to a binding post 49 carried by the upper plate 5. Leading from the binding posts 19 and 48 are the usual wires 50 by means of which the current is 70 75 conveyed to the lamp.

It will be readily seen from the foregoing that the current of electricity passes through the wire 22 to the wire 45 and through the same to the upper carbon 16 and that the 80 current is conveyed from the lamp through the arm 10 and the wire 48. When not in use, the upper and lower carbons are in contact with each other but as soon as the electric current passes into the lamp, the wire 85 22 becomes heated and expansion takes place which results in a lengthening of the wire allowing the spring 38 to move the end of the arm 31 to which it is connected upwardly and cause the upper end of the arm 90 41 to engage the upper carbon 16 as heretofore stated and lift the said carbon out of contact with the lower carbon of the lamp. As the upper carbon burns away and a greater length of arc is obtained, the wire 95 22 becomes cooled and hence contracts, resulting in a downward movement of the end of the pivoted arm 31 to which the spring 38 is connected, thereby releasing the end of the arms 41 from engagement with the upper carbon of the lamp and allowing the said carbon to move downwardly. It will of course be understood that although only one 100 of the clutch actuating arms and the clutch arms themselves have been described, I may 105 duplicate this construction when found necessary to suit certain conditions.

What is claimed is:

1. An arc lamp including a thermo expansive member comprising nickel, copper 110 and lead.

2. An arc lamp including a thermo expansive member consisting of an alloy comprising the elements and proportions substantially as follows: fifty-seven and one-half per cent. copper, forty-two per cent. nickel, and one-half of one per cent. lead. 115

In testimony whereof, I affix my signature, in presence of two witnesses.

CHARLES C. HUGHES.
